UNITED STATES PATENT OFFICE.

EMERY COULON, OF BLATON, BELGIUM, ASSIGNOR TO SOCIETE ANONYME SUPER-
TEXTILE, OF ANTWERP, BELGIUM.

MACHINE FOR REMOVING THE WOOD FROM RAMIE-STALKS IN THE DRY STATE.

1,054,753.

Specification of Letters Patent.

Patented Mar. 4, 1913.

Application filed September 16, 1912. Serial No. 720,646.

To all whom it may concern:

Be it known that I, EMERY COULON, a subject of the King of Belgium, residing at Blaton, in the Kingdom of Belgium, have invented certain new and useful Improvements in Machines for Removing the Wood from Ramie-Stalks in the Dry State, of which the following is a specification.

The present invention has for its object 10 a machine for the treatment of ramie stalks in the dry state with a view to eliminating therefrom the ligneous portions in order to obtain in the form of ribbons the fibers intended to be converted into harl by the subsequent removal of the pellicle and the gum which unites them.

The machine is of the known type in which the ramie stalks after having been crushed between pressure rollers, are conducted onto an anvil where they are struck by a rotary hammer constituted by a polygonal roller with rounded angles for breaking the wood into pieces which are then detached and removed from the fibers by rotary beaters. In the machines of this type such as hitherto constructed, the hammer only struck the stalks at intervals and left the whole of the operation of the detachment of the wood to the beaters. Then again, owing to the vigorous traction exerted by the beaters upon the stalks, the latter passed too rapidly beneath the hammer in the intervals between the blows and the result was that, as the intervals between these blows was excessive, the beaters had to detach excessive lengths of wood and frequently broke the fibers at the same time. Furthermore, owing to the want of resiliency in the hammer, it could not adapt its 40 blows to the variable thicknesses of the stalks so that sometimes the wood was insufficiently broken and sometimes the fibers were crushed and spoiled.

These defects are avoided in the present machine which is illustrated in side elevation in Figure 1 and in longitudinal section in Fig. 2 of the accompanying drawing.

In this machine, the bundles of dry ramie stalks, which are merely undone, are placed upon an endless apron 1 to which a movement of translation in the direction indicated by arrow 13 mounted upon the same shaft as the effect of the vibrations of the apron 1, the stalks are distributed over its entire width and pass between the crushing rollers 2 and

2' in the form of a uniform layer: these rollers are driven by the gear wheels 3 and 3' meshing together and driven by the operating hand wheel 6 through gear wheels 4 and 5.

In Fig. 2 the broken line b represents the path followed by the ramie stalks in the machine.

The crushing roller 2 is mounted upon a support 7 which is pressed downward by a spring 8 which enables it to separate slightly from the fixed roller 2' when hard bodies pass between them.

On leaving the crushing rollers, the rods pass onto the anvil 9 where they are struck by the angles of the hammer 10 actuated by a toothed wheel 11 upon which the chain 12 moves: this chain passes over the driving wheel 13 mounted upon the same shaft as the hand wheel 6. The anvil 9 is fixed and the hammer 10 is mounted in such a manner that it is able to experience slight displacements in the vertical direction, according to the thickness or the hardness of the material to be broken up. With this object its supports 14 rest upon springs 15 and are pressed downward by other springs 16. An adjusting screw 17 enables the tension of these springs to be regulated.

The hammer is square in section and the upper face of the anvil presents a very pronounced concave curvature and it is longer than its plane faces, in such a manner that one of the angles of the hammer invariably comes into contact with the stalks upon the anvil before the preceding angle has become disengaged therefrom completely. The broken stalks are pressed toward the beaters 18 and 19 owing to the rotation of the hammer 10; these beaters receive their movement from a chain 20 passing over the toothed wheels 21 and 22 and from the pinions 23 and 24. Each of the beaters 18 and 19 is constituted by two bars carrying at each of their extremities channeled bars 25 and 25' which strike the broken stalks and free the bark from the pieces of wood. The strips or ribbons thus formed fall onto an endless apron 26 constituted by a net, through the meshes of which the pieces of wood and the dust produced by the beating pass.

The operation of the machine is as follows: The bundles of ramie stalks are merely undone and placed upon the endless apron 110

1, the vibrations of which automatically distribute the stalks into a layer of approximately uniform thickness. This layer of stalks passes between the crushing rollers 2 and 2' and then onto the anvil from which it passes between the beaters 18 and 19. Owing to the traction of the beaters upon the stalks, the latter are stretched between the extremities of the anvil after each blow 10 of the hammer, then turned downward bent over the anvil by the next blow which serves to detach the wood. On the other hand, the angle of the hammer which reaches the stalks before the preceding angle has become completely disengaged therefrom, prevents the stalks from slipping upon the anvil, so that the breaks in the wood are closer together than in the known machines and consequently the wood becomes detached more 20 readily and the beaters have only to complete the detachment of smaller pieces of wood than hitherto and which are already detached to a large extent. The resiliency imparted to the hammer by the springs 15 and 16 prevents the crushing of the fibers at the places struck by the hammer. Finally the pieces of wood detached and the dust remaining in the fibers are separated by the vibrations of the openwork endless apron 25 upon which the fibers are discharged and fall between the meshes of this apron so that all the wood is removed automatically.

What I claim and desire to secure by Letters Patent of the United States is:—

35 1. A machine for removing the wood from ramie stalks in the dry state, comprising in combination a rotary hammer of polygonal

cross section, spring supports for this hammer and an anvil the concave face of which presents a curvature of which the axis of 40 the hammer forms the center and of which the length is greater than the distance between two consecutive angles of the hammer.

2. A machine for removing the wood from ramie stalks in the dry state, comprising in 45 combination a rotary hammer of square cross section, spring supports for this hammer and a trough-shaped anvil the concavity of which is longer than the distance between two consecutive angles of the hammer. 50

3. A machine for removing the wood from ramie stalks in a dry state, comprising in combination a rotary hammer of square cross section, spring supports for this hammer and an anvil the concave face of which 55 presents a curvature of at least a quarter circle, of which the axis of the hammer forms the center and ends in a rounded-off rear edge.

4. A machine for removing the wood from 60 ramie stalks in the dry state, comprising in combination a rotary hammer of square cross section, spring supports for this hammer and a trough-shaped anvil the concavity of which is longer than the distance between two consecutive angles of the hammer 65 and of which the rear edge is convex.

In testimony whereof I affix my signature in presence of two witnesses.

EMERY COULON.
